(57) **CLAIM**

We claim the ornamental design for the hair trimmer base with projections, as shown and described.

DESCRIPTION

FIG. 1 is a perspective view of the hair trimmer base with projections showing our new design.

FIG. 2 is a front end view of the hair trimmer base with projections shown in FIG. 1;

FIG. 3 is a back end view of the hair trimmer base with projections shown in FIG. 1;

FIG. 4 is a left side view of the hair trimmer base with projections shown in FIG. 1;

FIG. 5 is a right side view of the hair trimmer base with projections shown in FIG. 1;

FIG. 6 is a top view of the hair trimmer base with projections shown in FIG. 1; and,

FIG. 7 is a bottom view of the hair trimmer base with projections shown in FIG. 1.

The broken lines that are shown in the drawings illustrate the environment and form no part of the claimed design.

1 Claim, 6 Drawing Sheets
